CLAIM

The ornamental design for a digital clock, substantially
as shown and described.

DESCRIPTION

FIG. 1 is a front elevational view of a digital clock
showing my new design;

FIG. 2 is a top plan view thereof;

FIG. 3 is a right side elevational view thereof, the left
side being a mirror image thereto;

FIG. 4 is a bottom plan view thereof;

FIG. 5 is a rear elevational view thereof.
